United States Patent Office

Des. 179,155
Patented Nov. 6, 1956

179,155

SPECTACLE FRONT

Robert Passet, Vincennes, France, assignor to Societe Industrielle de Lunetterie, Paris, France, a French company

Application April 19, 1955, Serial No. 35,578

Term of patent 14 years

(Cl. D57—1)

Fig. 1.

Fig. 2.

I claim:

The ornamental design for a spectacle front, as shown.
